UNITED STATES PATENT OFFICE.

CHARLES DE LUKACSEVICS, OF WEST NUTLEY, NEW JERSEY, ASSIGNOR TO ANDREW GROSS, OF NEW YORK, N. Y.

VALVE FOR INTERNAL-COMBUSTION ENGINES.

1,244,711.

Specification of Letters Patent. Patented Oct. 30, 1917.

Original application filed November 17, 1913, Serial No. 801,533. Divided and this application filed April 6, 1914. Serial No. 830,049.

To all whom it may concern:

Be it known that I, CHARLES DE LUKACSEVICS, a citizen of the United States, residing at West Nutley, in the county of Essex 5 and State of New Jersey, have invented new and useful Improvements in Valves for Internal-Combustion Engines, of which the following is a specification.

My present invention relates to improvements in internal combustion engines and more especially to those of the multiple cylinder four-cycle type. The primary object of the invention is to provide improved valves for controlling the intake and exhaust ports of the various combustion chambers, tubular rotary water-cooled valves being preferably used, and the housings for such valves are detachably applied to the cylinder casings, enabling the valve housings to be renewed or replaced, if necessary, at small expense. A further object of the invention is to provide improved means for operating the valves and other parts from the crank shaft, the present application being a division of my prior application, Serial No. 801,533, filed November 17, 1913.

To these and other ends, the invention consists in certain improvements, and combinations and arrangements of parts, all as will be hereinafter more fully described, the novel features being pointed out particularly in the claims at the end of the specification.

In the accompanying drawings:—

Figure 1 represents a central vertical transverse section of a two-cylinder engine taken in the plane of the valves and constructed in accordance with the present invention;

Figs. 2-5 inclusive are horizontal transverse sections of the exhaust valve and its housing showing the positions of the exhaust valve corresponding to the different positions of the crank shaft;

Figs. 6-9 inclusive are similar views of the intake valve;

Fig. 10 represents a transverse section through the cylinders of the engine;

Fig. 11 represents, on an enlarged scale, a transverse section through the exhaust valve and its housing;

Figs. 12 and 13 are, respectively, a top plan view and a side elevation of the driving member for the exhaust valve.

Figs. 14, 15 and 16 are detail views of a modified form of valve driving member.

Similar parts are designated by the same reference characters in the several views.

Internal combustion engines constructed in accordance with the present invention are adapted to be utilized for various purposes, particularly where it is desired to obtain power with a motor of small size and relatively light weight. The preferred embodiment of the invention is shown in the accompanying drawings and will be herein-after described in detail, but it is to be understood that the present construction is but one example and the construction can be modified according to different requirements and also equivalent constructions may be employed which will be within the scope of the claims at the end of the specification.

In the construction shown, 1 designates the crank shaft which has two cranks 2 and 3 set at right angles and attached to the usual connecting rods. The ends of the shaft are mounted in the usual bearings in the ends of the crank case 4, the bottom of the crank case being closed by an oil pan 5 provided with the usual compartments in which the lower ends of the respective connecting rods dip and thereby effect lubrication of the bearings and other moving parts in the vicinity of the crank case. A spiral gear 6 is fixed to the crank shaft and serves, as will hereinafter appear, to operate the valves, this gear dipping into the oil contained in the oil pan and thereby effecting lubrication of these parts. A reservoir 7 is arranged below the oil can and contains a supply of lubricating oil, this oil being circulated from the reservoir to the oil pan by an oil pump 8 and the overflow returning to the reservoir through the vents in the upper wall 9 of the oil pan. The fly-wheel is fixed to one end of the crank shaft, as usual, and may serve in the usual way as one member of the clutch through which power is transmitted from the engine. The connecting rods 95 are connected to a pair of pistons which operate in the cylinders 9 and 10 respectively. The piston and cylinder arrangement as shown and described fully in my pending application above mentioned provides four 100 explosion or combustion chambers for each cylinder, the top and bottom combustion chambers 11 and 12 respectively, and the in-

termediate combustion chambers 13 and 14 respectively. Water jackets are provided to prevent excessive heating of these combustion chambers, as shown. The upper combustion chamber 11 of both cylinders communicates at one side of the engine with an intake port 15 and at the opposite side of the engine with an exhaust port 16. The lower combustion chamber 12 communicates 10 with similarly located intake and exhaust ports 17 and 18 respectively while the intermediate combustion chambers 13 and 14 communicate respectively with intake and exhaust ports 19, 20, 21 and 22.

15 In the present instance, the admission of fuel gas to both cylinders through the intake ports just described is controlled by a single rotary valve, and the present invention provides a valve and housing therefor which is detachably applied to the engine whereby it may be replaced, if necessary, at small cost. As shown, a valve housing 23 is fitted to one side of the cylinder casting and is removably secured thereto by 20 bolts or screws 24, as shown. This housing is bored in the form of a cylindrical valve chamber, and a hollow cylindrical valve 25 is fitted to revolve therein. This hollow cylindrical valve is formed in the present 25 instance with a set of four ports 26 corresponding to the intake ports 15, 17, 19 and 21, rotation of the valve operating to present these ports at appropriate intervals to the different intake ports whereby fuel is 30 admitted to the respective combustion chambers. In order to insure even distribution of the fuel gas through the length of the valve, a spiral or helically formed blade 27 is preferably provided, this blade being supported in stationary position within the hollow valve and rotation of the valve will cause the fuel gas to act on the spiral blade in a manner that will cause the fuel gas to rise or flow toward the top of the valve. 35 This valve is rotated continuously and at one half the speed of the crank shaft of the engine. The upper end of the valve is mounted in a bearing 28, and a bearing 29 supports the lower end of the valve. These 40 bearings support the weight and driving strain on the valves and hence minimize friction and wear between the valve and its housing. The exhaust valve is similar to the intake valve and it is applied in a similar 45 way to the opposite side of the engine. This exhaust valve is contained in a housing 30, the housing being fitted against the cylinder casting so as to control the exhaust ports 16, 18, 20 and 22, and is detachably secured in 50 position by the screws or bolts 31. This housing is bored to form a cylindrical valve chamber, and a cylindrical exhaust valve 32 is fitted to rotate therein. Preferably, 55 this valve is provided with a water jacket 33 to prevent excessive heating or warping

thereof. A set of four ports 34 is formed in this exhaust valve, they being spaced circumferentially and arranged at appropriate intervals to control the respective exhaust ports of the cylinders. The upper end of 60 this valve is provided with a bearing 35, and a driving shaft 36 below the valve is provided with a bearing 37, these bearings supporting and guiding the valve and thereby minimizing wear between it and its 65 housing. The driving shaft 36 may be connected to the valve by a coupling, either of the construction shown in Figs. 12 and 13, or one of the type shown in Figs. 14-16. In the former instance, the upper end of the 70 valve driving shaft 36 is formed with branches 38 which are connected at their upper ends to a circular flange 39, the latter being secured by screws or bolts to the lower end of the valve and having an opening 75 through the center for the passage of the exhaust gases. The shaft 36 is hollow for the passage of the cooling water and the arms or branches 38 of the coupling are also hollow to establish communication with the 80 water jacket of the valve. The coupling shown in Figs. 14-16 inclusive is similar to that just described, the upper end of the drive shaft in the latter instance being formed with up-turned arms 40 having 85 water passages 41 therein, and lugs 42 project from opposite sides of each arm and are secured to the lower end of the valve by screws or bolts. The coupling is centered 90 relatively to the valve by the upwardly projecting lugs 43 which enter the opening in the bottom of the valve. In the construction shown in Figs. 12 and 13, a circular rim 44 is adapted to enter the bottom of the valve and thereby center these parts. If desired, 95 the intake valve may also be provided with a water jacket to communicate with the water jacket of the cylinders, and in that case it will be constructed in a manner similar to the exhaust valve and will be provided 100 with a coupling similar to one of those just described. The upper end of the water jacket of the exhaust valve communicates with the water jacket of the cylinder through the connection 45 while the lower end of the 105 hollow valve driving shaft 36 communicates with the water-circulating pump 46, the latter being conveniently driven by the same shaft 36 which drives the valve. Also, the 110 oil pump 8 is preferably driven from the shaft which drives the intake valve, as shown. The intake and exhaust valves are driven by the spiral gear 6 which is fixed on the crank shaft and cooperates with complementary spiral gears 47 and 48 connected to 115 the intake and exhaust valves respectively. 49 designates the exhaust pipe which leads the consumed gases from the lower end of the exhaust valve, and 50 designates the carbureter which supplies the fuel gas to the 120

lower end of the intake valve. In order to prevent leakage, either or both of the valves may be provided with grooves or gas checks 51 and 52, and the corresponding housing 5 may be provided with similar grooves or gas checks 53, 54 and 55.

In the present instance where two cylinders are employed and one intake and one exhaust valve serve to control both cylinders, 10 the intake ports and the exhaust ports for one cylinder are separated by a partition from those of the other cylinder, as shown. Figs. 2-5 inclusive illustrate diagrammatically the relation between the exhaust valve 15 and the exhaust ports for two adjacent combustion chambers of the different cylinders during one revolution of the crank shaft. In these figures, the port *a* belongs to the cylinder containing the piston which is connected to the crank *x* shown by dotted lines. In Fig. 2 such crank has reached the end of its working stroke, the upper or corresponding exhaust port *a* being open. Fig. 3 shows the crank *x* a quarter turn on its upstroke, 20 the corresponding port *a* being still open and is closed when the corresponding crank *x* makes another quarter turn and thus completes its up-stroke, as shown in Fig. 4, it remaining closed during the next one-and-a-half revolutions of the crank shaft which 25 draws a charge of gas into this combustion chamber, compresses such charge and confines the same when exploded, according to the well-known four-cycle principle.

30 The lower port *b* in these figures which belongs to a combustion chamber of the other cylinder is timed to open and close according to the movements of the crank *y* shown in full lines. For example, in Fig. 30 35 40 45 50 55

2, this crank *y* is completing its working stroke, the corresponding exhaust port *b* being closed. In Fig. 3 this crank has reached the end of its working stroke and the valve has rotated into a position to open the corresponding exhaust port *b*, and this port remains open during approximately the next half revolution or up-stroke of its corresponding crank, as shown in Figs. 4 and 5, it being closed as the crank makes one-and-a-half revolutions from the position shown in Fig. 5 to complete the cycle as in the former case.

The intake ports of the different combustion chambers are controlled by the intake 55 valves in a similar way. In Figs. 6-9 inclusive, the upper port *c* belongs to a combustion chamber of the cylinder containing the piston which is connected to the crank *x*. This crank is commencing its suction 60 stroke in Fig. 6 and the valve is about to open the port *c*. Fig. 7 shows the crank *x* midway of its suction stroke and the port *c* fully open. Fig. 8 shows the crank *x* at the

end of its suction stroke and the port *c* closed. In Fig. 9, the crank *x* is midway 65 of its compression stroke, the port *c* being still closed and remaining closed until the crank *x* has completed its suction, power and exhaust strokes as in engines operating upon the well-known four-cycle principle. 70 The port *d* is timed to open and close according to the movements of the crank *y*, it opening when this crank commences its suction stroke, as shown in Fig. 7, remaining open until this crank completes its suction stroke, as shown in Figs. 8 and 9, thereupon closing and remaining closed while this crank makes its compression, power and exhaust strokes as in the preceding instance. In the present arrangement, it is 80 to be understood that each valve turns at one half the speed of the engine or crank shaft. This invention enables single intake and exhaust valves to be used to control the various combustion or explosion chambers of both cylinders, thereby reducing the number of parts to a minimum, and the valves and their housings can be replaced if such should become necessary, thus saving the cylinders, 85 pistons and other parts of the engine. 90

What is claimed is:—

1. In an internal combustion engine, the combination of a water-jacketed cylinder, valve revolvably mounted thereon, said valve having therein an axially extending fluid 95 passage open at one end and having ports at intervals in its length to coöperate with the cylinder ports, and a water jacket extending longitudinally and exteriorly of said passage, means connecting one end of the water jacket of said valve with the cylinder water jacket, a hollow driving shaft at the opposite end of the valve, and a coupling connecting the open end of the valve and the adjacent end of the driving shaft and having arms provided internally with water passages connecting the interior of the having shaft with the water jacket of the valve, the arms being spaced to expose the open end of the valve. 100 105 110

2. In an internal combustion engine, a rotary intake valve having an axially extending fuel passage with ports at intervals in its length to coöperate with the cylinder ports, means for supplying fuel to one end of the axial fuel passage of the valve, and a helically formed blade supported in fixed position within said axial fuel passage in the valve and extending past the ports thereof. 115

In testimony whereof I have hereunto set my hand in presence of two subscribing witnesses. 120
